UNITED STATES PATENT OFFICE

2,599,712

TABLE-TOP PROCESSING MACHINE

Manuel Izen, Los Angeles, Calif.

Application December 8, 1950, Serial No. 199,801

6 Claims. (Cl. 144—144.5)

1

This invention relates to machines employed in the furniture and kindred industries, and particularly to a machine for applying metal moulding or trim strips to the edges of table tops and the like.

In applying a moulding or trim strip to the peripheral edge of a table top it is customary to first shape the table top and groove the edge thereof, said groove extending lengthwise throughout the edge or edges to which the moulding strip is to be attached. The narrow groove is usually cut into the edge of the wooden table top by means of a thin rotary cutter which is either moved along the edge or is fixedly mounted and operative to cut the groove in the table top which is moved with respect to the cutter. After being thus grooved, the table top is provided with a metal trim strip which has a longitudinally extending fin or web on its rearward side, the fin being adapted to be forced into the peripheral groove of the table top to anchor the strip in place. The step of applying the trim strip to the table top is usually carried out by placing the strip with its anchoring fin in alignment with the groove and tapping the strip to cause its fin to enter the groove and to become firmly wedged therein, the tapping being accomplished manually through the use of a relatively soft hammer. Following this step, the table top is placed in a frame-like press which completes the strip-applying operation by applying uniform pressure against the strip to iron out wrinkles which may occur therein due to the previous hammering operation. It is thus seen that the applying of metal trim or moulding strips to the edges of table tops entails a relatively slow procedure, which is reflected in a high cost of production and thereby a relatively high retail price to the consumer.

It is an important object of this invention to provide a machine or apparatus which is operative to shape the table top and cut or mill a groove in the periphery of the same, and to apply a metal trim moulding to the grooved edge of the object.

Another object is to provide a machine, of the character referred to, in which the table top is carried by a turntable which is rotatable on a vertical axis, and in which a thin rotary gang cutter is mounted to move toward and away from the edge of the table top, the cutter, when disposed adjacent the table, being adapted to shape the table top and cut a continuous groove in the edges as the table top is rotated.

Another object is to provide a machine, of the

2

class referred to, in which the turntable includes a flat, plate-like pattern upon which the table top rests, the pattern being of the same shape but of somewhat smaller proportions than the table top being processed, the machine further including a follower roller disposed coaxially of the cutter and arranged therebelow, the roller being adapted to roll along the edge of the pattern to control the depth of the groove being milled in the table edge by the rotary cutter. A related object is to provide spring means operative to normally elevate the cutter assembly, this means being yieldable to allow the assembly to be moved downwardly so as to dispose the follower roller beneath the edge portion of the table top. By this means, the follower roller is held against the lower surface of the table top so as to cause the groove to be cut parallel to the plane of the table top, this being important to insure that the upper edge of the trim strip will align with and not extend above the upper surface of the table top.

Another object is to provide a machine of the type indicated which includes a vertically movable and rotatable ram adapted, when in lower position, to hold the table top firmly in place upon the pattern.

A further object is to provide an electric motor-driven speed-reduction driving unit for rotating the pattern which supports the table top being operated upon, the motor being of the reversible type and operative in response to a manual control.

A still further object is to provide means embodied in the machine for applying the metal trim strip to the grooved edge of the table top, this means consisting of a resilient roller engageable with the strip and rollable therealong as the table top is rotated so as to force the wedge-like anchoring fin into the groove with a rolling action. A related object is to provide a fluid-actuated jack for forcing the roller against the trim strip and table top, the jack including a bleed port by which the fluid pressure in the jack cylinder is relieved as the piston, which is operatively connected to the pressing roller, is forced in reverse direction as the roller follows the contour of the table top. A further object in this respect is to provide a readily accessible control valve by which fluid can be introduced into either end of the jack cylinder to move the roller against the table top and to retract the same therefrom.

Further objects will appear from the following description and from the drawings, which

are intended for the purpose of illustration only, and in which:

Fig. 1 is a perspective view of the machine for applying metal trim strips to the edges of table tops or the like;

Fig. 2 is a perspective view of a table top section, showing a metal moulding or trim strip applied to the edge thereof;

Fig. 3 is a cross-sectional view of the edge portion of the table top component, taken on line 10 3-3 of Fig. 2;

Fig. 4 is a sectional plan view of the machine, taken substantially on line 4-4 of Fig. 1, the rotary cutter means being shown in its operative position at the start of the grooving operation; 15

Fig. 5 is a view similar to Fig. 4 but showing the grooving means in its inoperative position and illustrating the trim strip applying means operative to press the trim strip in place; and

Fig. 6 is a vertical sectional view, taken on line 20 6-6 of Fig. 4.

Referring to the drawings in detail, the present machine is designed primarily for use in applying a metal moulding or trim strip 10 to the perimetrical edge of a table top or a section of such a top, such a section or component being designated by the reference numeral 11 in the drawings. The metal strip 10 may be of a width substantially equal to the thickness of the table-top, or it may be relatively wide to adapt it to extend below the bottom surface of the table-top as shown in Figs. 2 and 3. In either case, the trim strip is provided with a rearwardly projecting, longitudinally extending fin or web 12 which, as shown in Fig. 3, has barb-like ribs 13. The table-top component 11 and its trim strip 10 are conventional in tables of the so-called chrome furniture class in which the table is provided with a hard, plastic upper surface 14.

As previously explained, the chrome-plated trim strip 10 is secured to the edge of the table-top, or a section thereof, by first shaping the section and cutting a slit or groove in the edge of the same, and thereafter placing the strip adjacent the edge with its rearward fin 12 in alignment with the groove, after which the strip is forced against the shaped edge to cause its barbed fin to become firmly wedged and embedded in the table-top. Fig. 3 illustrates the strip 10 applied to the table-top section 11 with its anchoring fin 12 firmly wedged in the narrow groove, which is designated by the reference numeral 15. As stated before, the operations of grooving the table-tops and attaching the trim strips thereto have heretofore been costly since they have been carried out manually. It is the aim of this invention to provide a machine for carrying out the method systematically and semiautomatically so as to simplify the operations, greatly improve the product and minimize the cost of production.

Referring first to Fig. 1, the present machine or apparatus comprises a relatively heavy frame 20 made from structural steel elements, the frame including a pair of uprights or stanchions 21 and 22 between which extends a lower beam 23, and upper beam 24 and intermediate beams or cross members 25 and 26.

Rotatable in bearings 27 and 28 carried by the respective beams 23 and 26 is a vertical shaft 36 which, as shown in Figs. 4 and 5, carries a large gear 31. Supported by a bracket 32, secured to the upright 22, is a reversible electric motor 33 and a speed reduction unit 34 operatively associated with the motor to be driven thereby, the unit being of a conventional type and including an output shaft 35 having a gear 36 thereon

which meshes with the gear 31 to rotate the same when the motor 33 is energized. The gears 33 and 36 are enclosed in a cover or guard 37.

The shaft 30 projects above the beam 26 and has a circular plate 40 which provides a turntable. Secured to the upper surface of the turntable 40, as by screws, is a pattern or template 41 which follows the general contour of the table-top or table-top section 11 to be operated upon, the pattern being, however, somewhat smaller than the section 11 as shown in Figs. 4 to 6.

The table-top section 11 is adapted to be supported upon the turntable 40 and to be rotated at a relatively slow speed therewith. Since it is highly desirable that the section 11 be quickly insertable in and removable from the machine, the present machine embodies readily releasable means for clamping the section in place. This means comprises a clamping plate or head 42 which is carried by the piston rod or ram 43 of a fluid-actuated jack 44, the latter including a stationary cylinder 45 into the upper and lower ends of which pressure operating fluid can be selectively introduced by way of pipes 46 and 47. Flow of fluid through the pipes 46 and 47 is controlled by means of a selector valve 48 through which the fluid is forced by a pump (not shown) which draws the fluid from a reservoir 49. After the table-top section 11 has been placed in the turntable 40 in correct position, the valve 48 is actuated to cause the piston rod 43 to be lowered. By this procedure, the clamping plate 42 is caused to descend against the table-top section 11 to clamp it firmly against the turntable 40. The piston rod 43 is rotatable in the cylinder 45 so that when the turntable is rotated, for the purpose to be later explained, the clamping plate 42 rotates with the table-top section 11.

Pivoted on a vertical support rod 55 are the arms 56 of a carrier member 57, the forward end of which is disposed forwardly of the frame 20. The carrier member 57 supports an electric motor 58 whose vertical armature shaft 59 carries a pair of cutter discs 50 and 51 between which is disposed a thin cutter disc or saw 60. The carrier member 57 is normally elevated by means of a coil spring, indicated generally at 61, and is adapted to be pivoted toward and away from the turntable 40 by means of a handle 62 projecting from the member. The armature shaft 59 also carries a follower disc 63 which is of larger diameter than the gang of cutter discs 50, 51, and 60, and disposed therebeneath.

When the cutter unit 57, 58, 60 is moved toward the turntable 40 and is depressed, the follower disc 63 is caused to underlie the edge portion of the table-top section 11 and to engage against the perimeter of the pattern or template 41. The relative diameters of the follower disc 63 and the rotary cutters 50 and 51 is such that the latter act to plane the edge of the table-top section 11 and its covering 14 so as to shape the same to the correct contour and size, engagement of the follower disc with the pattern 41 controlling the movement of these cutter discs. As the turntable 40, and the section carried thereby, are rotated slowly, the rotating cutter 60 acts to mill the continuous groove 15 in the shaped edge of the table-top component 11. The carrier member 57 may be readily raised or lowered by means of handle 63 pivoted on the frame 20 and operatively connected to the rod 55. When the cutter unit is not in operation, it can be retained against the upright 21 by means of a hook-type latch 66.

To shape the table-top section 11 and cut the groove 15 therein, the turntable 40 is rotated to the position shown in Fig. 4, at which time the cutter unit is swung toward the right and lowered to dispose its follower disc 63 beneath the section, in engagement with the pattern 41. The turntable is then rotated in clockwise direction, as viewed in Fig. 4, while the cutter unit is urged toward the right to maintain the follower disc 63 in rolling engagement with the pattern. While the cutter unit is herein shown as manually operated, it will be apparent that it may be maintained in co-operative relation with the table-top section 11 by suitable fluid-actuated or spring means. After the cutter 60 cuts the groove 15 in the three outer edge portions of the table-top section, the trim strip 10 is applied to these edge portions by mechanism to be next described.

Pivoted on a vertical rod 70, mounted at the rear of the frame 20, is a pair of arms 71 and 72 which extend forwardly through the space between the cross-beams 25 and 26. Extending between the forward ends of the arms 71 and 72 is a vertical stub shaft 73 upon which is rotatably mounted a resilient roller 75. Connected between the forward ends of the arms 71 and 72 is a curved yoke 76 to which is pivotally joined the piston rod 77 of a fluid-actuated jack 78. The jack cylinder 79 is pivotally connected at 80 to arms 81 and 82 projecting from the upright 22. Operating fluid is selectively introduced into either end of the cylinder 79 through lines 83 and 84 which are connected to a selector valve 85.

When it is desired to apply the trim strip 10 to the grooved edges of the table-top section 11, the latter is first rotated to the position illustrated in Fig. 5. One end of the trim strip 10 is then placed against the table-top section 11. The valve 85 is then actuated to introduce fluid into the right-hand end of the cylinder 79 so as to cause its piston and the piston rod 77 to be extended toward the left. By this action, the arms 71 and 72 are pivoted toward the left so as to engage the pressing roller 75 against the trim strip. The motor 33 is then energized to cause it to rotate the turntable in counterclockwise direction. During such rotation of the section 11, the roller 75 acts to press the trim strip 10 firmly against the grooved edge and to thus force the barbed rib 12 into the groove. In order to allow the roller 75 to follow the contour of the table-top section 11, the cylinder 79 is provided with a bleed port having a relief valve incorporated therein, this being a common expedient and therefore not shown in detail. While the drawings illustrate the table-top section 11 as being of substantially rectangular shape, it will be apparent that the present machine is adaptable for use in applying trim strips to table tops, or sections thereof, having different shapes. For example, the machine is adapted to apply trim strips to circular table tops, to semi-circular table-top sections or leaves, etc.

After the trim strip 10 has been applied in the manner explained above, the roller 75 is retracted and the clamping head 42 is raised by manipulating the valve 48. The table-top section 11 thus is released and may be conveniently removed from the machine and replaced by another ungrooved section, after which the operative cycle is repeated.

While the machine or apparatus has been described as embodied in a preferred form of construction, by way of example, it will be understood that various modifications might be made

in its structure without departing from the spirit of the invention. Consequently, I do not wish to be limited in this respect, but desire to be afforded the full scope of the appended claims.

I claim as my invention:

1. In a machine for applying a trim strip to the edge of a flat object: a frame; a flat pattern rotatable on said frame and supporting the object, said pattern having a perimeter conforming generally to the perimetrical contour of the object; releasable clamping means for clamping the object to said pattern; a carrier movable on said frame; a cutter rotatable on said carrier, said carrier being movable to an operative position to dispose said cutter in cutting engagement with the edge of the object, rotation of said object relative to said carrier causing said cutter to cut a groove in the perimeter of the object; a follower roller disposed coaxially with said cutter and rollable along the perimeter of said pattern, said pattern being of smaller dimensions than the object and said roller being of larger diameter than said cutter so as to control the depth of the groove cut by said cutter; and a spring operative to move said cutter axially into engagement with a face of the flat object so as to position said cutter at a selected distance from said face transversely of the object, said spring being engageable between a part of said frame and said carrier.

2. In a machine for applying a trim strip to the edge of a flat object: a frame; a flat pattern rotatable on said frame and supporting the object, said pattern having a perimeter conforming generally to the perimetrical contour of the object; fluid-actuated, releasable clamping means for clamping the object to said pattern; a carrier movable on said frame; a cutter rotatable on said carrier, said carrier being movable to an operative position to dispose said cutter in cutting engagement with the edge of the object, rotation of said object relative to said carrier causing said cutter to cut a groove in the perimeter of the object; a follower roller disposed coaxially with said cutter and rollable along the perimeter of said pattern, said pattern being of smaller dimensions than the object and said roller being of larger diameter than said cutter so as to control the depth of the groove cut by said cutter, said carrier being movable in a direction axially of said cutter; and a spring having one end engaging a part of said frame and its other end engaging said carrier so as to move the latter in a direction to maintain a face of said follower in engagement with a face of said pattern adjacent its edge and thus position said cutter at a predetermined distance from said face transversely of the object.

3. In a machine for applying a trim strip to the edge of a flat object: a frame; a flat pattern rotatable on said frame and supporting the object, said pattern having a perimeter conforming generally to the perimetrical contour of the object; fluid-actuated, releasable clamping means for clamping the object to said pattern; a carrier pivoted on said frame; a cutter rotatable on said carrier with its axis vertical, said carrier being movable to an operative position to dispose said cutter in cutting engagement with the edge of the object, rotation of said object relative to said carrier causing said cutter to cut a groove in the perimeter of the object; and a follower roller disposed coaxially with said cutter and rollable along the perimeter of said pattern, said pattern being of smaller dimensions than the ob-

ject and said roller being of larger diameter than said cutter so as to control the depth of the groove cut by said cutter, said carrier being movable vertically so as to dispose said cutter at desired distance from a face of the object; and a spring having a lower end engaging a part of said frame and its upper end engaging said carrier so as to normally urge said carrier upwardly to maintain the upper face of the follower in engagement with the lower face of the object, so as to cause said cutter to cut the groove at a predetermined distance from said bottom face.

4. A machine of the character defined in claim 3 and including a coil spring compressed between a part of said frame and said carrier so as to move said carrier in a direction to maintain said follower roller flat against a face of the object so as to locate said cutter at a predetermined distance inwardly from said face.

5. In a machine for applying a trim strip to the edge of a flat object; a frame having a vertical post; a flat pattern rotatable on said frame and supporting the object, said pattern having a perimeter conforming generally to the perimetrical contour of the object; releasable clamping means for clamping the object to said pattern; a carrier pivotally mounted for horizontal pivotal movement and slidable vertically on said post; cutter means rotatable on a vertical axis on said carrier, rotation of said object relative to said carrier causing said cutter means to shape the perimeter of said object and cut a groove in the perimeter of the object; a follower roller disposed coaxially with said cutter means and rollable along the perimeter of said pattern, said pattern being of smaller dimensions than the object and said roller being of larger diameter than said cutter means so as to control the contour of the object and the depth of the groove cut in its edge; and a spring surrounding said post and engaging between said frame and said carrier for normally moving the latter upwardly to maintain said follower roller in engagement with the bottom face of the object.

6. In a machine for applying a trim strip to the edge of a flat object; a frame; a flat pattern rotatable on said frame and supporting the object, said pattern having a perimeter conforming generally to the perimetrical contour of the object; releasable clamping means for clamping the object to said pattern; a carrier pivoted on said frame for movement toward and away from the perimeter of the object and in a plane of said object, said carrier being also movable in a path extending at right angles to the plane of said object; cutter means rotatable on said carrier for grooving the perimeter of said object; a follower roller disposed coaxially with said cutter means and rollable along the perimeter of said pattern, said pattern being of smaller dimensions than the object and said roller being of larger diameter than said cutter means so as to control the depth of the groove cut in its edge; and a spring engageable between a part of said frame and said carrier and normally operative to move the carrier in a direction to maintain said follower roller in engagement with a face of the object so as to locate the groove at a predetermined distance from a face of the object.
